INDIVIDUAL PACKAGING APPARATUS,
METHOD, AND PACKAGE
Howard Nelson Moore, Apt. 201, 1901 East West
Highway, Silver Spring, Md.
Filed Oct. 7, 1957, Ser. No. 638,756
18 Claims. (Cl. 53—21)

The present invention concerns the packaging of a number of relatively similar objects, articles or units of material in a multicompartimental package, and the preservation of the packaged units.

Reference is made to U.S. Letters Patent No. 2,255,432, granted to me September 9, 1941, on analogous subject matter, for supplementary disclosure and background.

The present application is a continuation-in-part of my copending applications Serial No. 411,235, filed September 17, 1941, now abandoned in view of Serial No. 92,476, filed May 10, 1949, now U.S. Patent No. 2,808,691, granted October 8, 1957, and Serial No. 454,912, filed September 9, 1954.

It is an object of the invention to provide a package of similar units of material which are individually wrapped, each unit being sealed against contamination or change by any foreign matter, bacteria, moisture, undesired oxidation, other undesirable chemical changes, or the like. The present invention provides a package comprising individual units of similar character which are contained in individual compartments formed of cup-shaped elements which may overlap in sealing relation one with the other to form a unitary package of substantial strength whereby to guarantee the integrity of the sealed character of the individual compartments.

It is an object of the invention to package individually, like units of material comprising candy lozenges, candy mints, pigments, putty, extracts, chemicals, tablets, pharmaceuticals, slices of bread, cakes, cookies, cheese, fish, sea food, meat, meat products, tobacco, spices, tea, sugar, flour, meal and without limitation, loose materials of all kinds, including granulated, powdered or viscous materials and liquids. These products may be packaged in measured units to facilitate use without waste and to achieve a desired result. Diverse articles may be packaged such as complete meals, food and drink mixes, sandwiches, condiments or any compound ready mixed or in its component parts.

It is an object of the invention to provide a package for individual units of perishable materials, such as pharmaceuticals, chemicals, foodstuffs and the like which can be irradiated by fissionable material or a radiation generating device, or any suitable radioactive material or source.

The radiation herein referred to may be low level radiation of materials before packaging or preferably of the packaged material with all coverings and seals intact. Although low level radiation is at the present time preferred because it provides adequate normal protection to the otherwise perishable contents without interference with taste, odor, or other characteristics, the invention is not limited to this type of irradiation. Where the objection to discoloration, changes in smell, and taste, are not limiting factors or they are controllable within acceptable limits, the invention is intended to be utilized for the packaging of food which is sterilized completely whereby refrigeration can, in most cases, be dispensed with entirely. Such packages may be used in the field on long trips or merely stored on a shelf and used a unit at a time as required.

While the present technique of relatively low level irradiation for pasteurization is preferred, and it is not

2

intended for normal use to make the packages or their contents radioactive, such treatment is not precluded where the maintenance of the otherwise perishable contents under highly adverse conditions is paramount to taste, smell and other requirements regarding changes in characteristics. Even in these cases, sterilization is all that would be required and it is only where there is danger of contamination from the outside by penetration or rupture of the compartment walls or the sealed joints that radioactivation of the contents, however mild, is resorted to. Until these techniques are improved, it is contemplated that the pasteurized packages of the more delicate or more perishable foods will be refrigerated as well.

15 The air contained in the individual compartments of the package may be withdrawn and replaced by an inert gas such as nitrogen or other air which has been sterilized. Nitrogen, carbon dioxide, argon, neon or the like are preferred where oxidation is a deleterious factor. If desired, the sterilized air or inert gas itself may be radio-activated before injection in those cases where a long period of storage under highly adverse conditions is contemplated. If any chemical reaction, perfuming effect, coloring, taste, texture or food value change or any other chemical or physical combination or mixture is desired, the proper gas or material may of course be introduced during packaging or later.

20 It is to be understood that in all cases where the package and its contents are radioactivated, sufficient shelf life or other storage time must be allowed prior to human consumption to assure against poisoning from this source. Such packages, as well as those just discussed above, are preferably dated, showing time of sealing or the date after 25 which they may be opened and used with good effect and safety.

It is an object of the invention to provide means for producing a package of a number of articles which are individually wrapped.

30 40 It is an object of the invention to provide means for producing a package containing a number of substantially sterile articles, each of which is sealed against contamination by any foreign matter, moisture or the like.

45 The present invention provides a device whereby individual units of similar character may be rapidly and securely packaged individually by a single strip of paper. While the invention is primarily intended to package relatively small articles such as lozenges, candy mints, tablets, pharmaceuticals, it nevertheless may be applied 50 to much larger things such as slices of bread, cakes, cookies or anything which is fairly regular in outline and has two reasonably flat surfaces.

55 It is not, however, limited to such articles and may be utilized to package loose material such as tobacco or sugar which need not necessarily be compressed into tablet form. The invention finds an important application in the field of food packaging. Many perishable foods, for example meat patties, may be packaged individually in the same package by the present invention

60 and may thereby eliminate the need of refrigeration where the food product has been irradiated, mixed with antibiotics, or other preservative means employed. It will be appreciated that the opening of one or more compartment units will neither disturb nor contaminate 65 the remainder of the package. While the units need not be round, they should preferably be substantially uniform in shape.

70 The term "article" is used herein as a thing of a particular class or kind, as defined at page 156 of Webster's New International Dictionary, Second Edition, Unabridged, G. & C. Merriam Company, publishers, 1947.

The present invention may utilize a feeding table in

the central portion of which is an aperture of such size as to receive the article. The aperture is surrounded by a depending tube with a flaring lip. A roll of wrapping paper of suitable width is disposed at one side of the table and led by suitable guides and feeding rollers across the aperture. Above the aperture is positioned a die punch. The paper is fed across the aperture by suitable mechanism and the article to be wrapped positioned thereon. A die punch is then lowered to cut a suitable blank from the paper. The edges of the blank may be tongued or not as desired. A punch which is associated with the die structure forces the article to be wrapped and the small paper blank upon which it rests into the flaring mouth of the aperture. There is sufficient margin provided on the paper blank to leave an upstanding annular collar extending well above the article to be wrapped. The article rests within the tube in a dish-like compartment, the top of which is open. The feeding rollers advance the paper strip so that it again covers the aperture and a second article is deposited thereon over the aperture and substantially centrally thereon. The die punch again descends, cuts a second blank and forces the article and the blank on which it rests into the tube on top of the first article. The second blank will be seen to form a cover for the first article and the marginal portion of the first blank will extend up around the sides of the second article on the outside of the second blank. This operation is repeated and the articles force each other down the tube which, after the mouth portion is passed, is of such diameter as to cause the marginal portion of the blanks to fit snugly against the outside of the side of the next succeeding article and blank. The tongued portions permit easy overlap at this stage. The paper may be waxed, coated, or of heat sealing cellophane or the like. A portion of the periphery of the tube may be heated by any suitable means such as a heating coil, causing the marginal portions of the blanks which are folded against the sides of the succeeding blanks to adhere thereto in a vapor-proof gas-tight seal. The article is entirely enclosed between the two blanks in an individual compartment. If desired, the die punch structure may be made hollow and the articles deposited on the paper strip over the aperture from a magazine feed in the hollow portion of the punch. In this way the article is deposited substantially simultaneously with the dieing out of the paper blank. A perhaps simpler construction may be obtained by employing a separate mechanism for positioning the articles. This is particularly true where some variation in size must be dealt with. If desired, pre-formed cups may be used to form the package by nesting them in the tube where the cup walls overlap and are sealed. The invention also embraces compartments formed in a plastic material wrapper by twisting the individual compartment portions. The twisting can all be in the same direction or reversed, as to alternate compartments. Pre-formed cups may also be pre-filled.

In addition to the other means for the preparation of food, disclosed herein, it is an object of the invention to use the penicillins and the mycins, such as aureomycin, alone or together with similar and related antibiotics, which shall be selected for their disinfecting or antibiotic properties, with a minimal effect on taste and color. These substances may be added to the foods prior to packaging, and mixed therewith or sprayed thereon as desired. Again, the method of food preservation employed herein may utilize short sound waves which are ultrasonic in character, alone or in addition to the irradiation discussed at length. It is also contemplated that dehydrofreezing, that is deep or quick freezing with small crystal formation supplemented by sublimation of the ice crystals with or without the application of a vacuum, may be incorporated as steps in the process of forming a package according to the invention. It will be understood that in order to maintain quality

with minimum deleterious action on the packaged foods two or more of the above preserving means or processes may be employed in combination or successively on food to be packaged or food in the packages.

FIGURE 11b is a section along line 11—11 of FIGURE 10b.

FIGURE 12b is a section of a modified form of the invention.

FIGURE 13b is an enlarged section of the package of FIGURE 9b without an outer wrapper.

FIGURE 14b is an enlarged section of the package of FIGURE 9b with a modified closure.

FIGURE 15b is an enlarged section of the package of FIGURE 9b with a closure such as shown at the top of FIGURE 1b.

FIGURE 16b is a modified form of the invention for packaging larger flat units such as slices of bread, hamburger patties, cheese slices, luncheon meat, sandwiches and the like.

FIGURE 17b is a section of a modified form of package using an outer wrapper shell.

FIGURE 18b is a sectional elevation of one form of spacer or support element to be employed where the packaged contents are fragile or delicate in one sense or another.

FIGURE 19b is a section closure or spacer element which may be employed in certain forms of the invention.

One form of the invention comprises a machine frame 10 of usual construction which supports a table 11 having a central aperture 12. An annular guide ring 13 is mounted on the under side of the table 11 and surrounds aperture 12. A tapered channel 14 in ring 13 connects aperture 12 and tube 15 which is mounted on the under surface of ring 13. Aperture 12, channel 14 and tube 15 are aligned and form a continuous passage which is progressively smaller in cross sectional area from aperture 12 to the upper end of tube 15. While aperture 12 and channel 14 are shown as frusto conical and tube 15 is cylindrical it will be understood that these elements may have polygonal, elliptical, or any other suitable cross-section to conform with or to form the packaged units or the package produced. The lower end of tube 15 may have a somewhat enlarged diameter at 16 and may be connected with another tube or slide to deliver completed packages to a box or other grouping of packages as a merchandizing sales package.

At one side of aperture 12 a narrow roll 17 of strip packaging material such as waxed paper, coated heat or pressure sealing cellophane, coated heat or pressure sealing foils or the like is mounted at 18 on frame 10 and table 11. The narrow strip 19 is lead over curved guide 20, along the upper surface of table 11 between feed rolls 21 and 22 and over aperture 12 to a very slightly raised stop edge 23 in table 11. Table 11 is constructed with its upper surface at two slightly different levels, that portion to the left of stop edge 23 in FIGURE 1 being higher than the portion to the right by the thickness of strip 19. Additional feed rolls 21, 22 may be provided if desired to assure that strip 19 lies flat and does not buckle.

A guide sleeve 24 is supported by frame 10 directly over aperture 12 in table 11. A cutter member 25 is slidably

mounted within guide sleeve 24 and provided with an annular cutting edge 26 and radial slitting knives 27. Annular cutting edge 26 dies out a circular blank from strip 19 and radial knives 27 cut radial slits in the outer edge of the blank. Where pucker is a problem slitting knives 27 may take the form shown at 28 and remove small wedge-shaped sectors from a blank.

Centered within guide sleeve 24 is a tube 29 which makes sliding contact with an air tight packing gland 30 in the upper closed end 31 of guide sleeve 24. An annular piston plate 32 is mounted on tube 29 at 33 and slides smoothly within the guide sleeve 24. A coil spring 34 is connected at one end to the lower side of annular piston 32, at the end to the upper side of cutter member 25 and surrounds that portion of the tube 29 between piston 32 and cutter 25. Mounting means 33 firmly unites piston 32 and tube 29, but cutter member 25 can slide relative to both sleeve 24 and tube 29 under the reaction of the cutting force exerted on strip 19 and the effect of spring 34.

Tube 29 may contain a central resilient plunger element 35 of rubber or the like as shown in FIGURE 1, or it may contain a series of closure members 36 of cardboard, fiber, plastic or other material as shown in FIGURE 3. Where closure members 36 are employed tube 29 extends upward into a supply hopper in which it reciprocates under the combined action of piston 32 and restoring spring 37. Restoring spring 37 is anchored to the inner wall of sleeve 24 by bolts 38 and acts against the under surface of piston 32. It is to be understood that although sleeve 24, cutter member 25 and tube 29 are shown as circular in cross-section they may be of any shape suitable to cooperate with aperture 12, channel 14 and tube 15.

As will be seen in FIGURE 3 the upper portion of sleeve 24 between end closure 31 and annular piston 32 comprises pneumatic cylinder to which air under suitable pressure is supplied from compressor-reservoir combination 39 by pipe 40. A combination control and bleed valve 41 is connected in pipe 40 and is operated by solenoid 42 connected in turn to control panel 43 by lead wires 44.

Closure member ejector 45 is mounted on an inner wall of sleeve 24 with the pneumatic cylinder portion. Ejector 45 comprises a pointed armature 46 movable toward closure elements 36 under the action of energizing winding 47 connected to control panel 43 by lead wires 48. A light compression spring 49 maintains armature 46 inoperative when winding 47 is not energized. Armature 46 operates by extending through slot 50 in tube 29 and holding the column of closure members 36 stationary momentarily until the lowest element 36 is ejected from tube 29.

An article supply tube 51 is mounted on frame 10 adjacent sleeve 24. Supply tube 51 may be connected to a hopper or other supply for continuous feed of articles 52 to be packaged or the tubes 51 may be replaceable when empty. Beneath article supply tube 51 is mounted article positioning arm 53 having a curved article receiving face portion 54 and an elongate arcuate tail portion 55. Tube 51 is raised sufficiently above table 11 to allow ample clearance for the passage of arm 53 and a single article 52. Arcuate tail portion supports the remaining articles 52 until arm 53 is returned. Arm 53 is operated by a spring return solenoid 56 and pivoted connecting rod 57 with suitable linkage. Solenoid 56 is connected to control panel 43 by lead wires 58.

Feed rolls 21 and 22 are driven by motor 59 connected to control panel 43 by lead wires 60. Motor 59 delivers just the right amount of strip 19 without drift.

Where the outline of cutting edge is other than rectangular an edging knife 61 is mounted on cutter member 25 by stud bolts 62 which move in slot 63 in guide sleeve 24. Trimmings are removed through cleaner channel 64 connected with a suitable source of low pres-

sure and having a valve 65 operated by the descent of cutter member 25 or synchronized therewith through lead wires 44. Instead of using knife 61, roll 22 may be a serrating roll of a circumference equal to the length of wrapping portion 79 and positioned close enough to aperture 12 that only a single serration 89 exists in strip 19 at any one time.

In that form of the invention which employs resilient plunger element 35 instead of closure members 36 closure of a package is effected in a different manner. A solenoid 66 is mounted on the underside of table 11. A depending arm 67 provides a pivot for bent lever arm 68 one end of which is connected to plunger 69 of solenoid 66 and the other end has a widened package engaging portion 70. An elongate slot 71 in the lower part of tube 15 permits the passage of lever portion 70 which may be curved to fit the bottom of the package. Lead wires 72 connect solenoid 66 to control panel 43 and may have a suitable delay device or network 73 in the circuit.

Top closure forming mold 74 is mounted on top of table 11 on an arm 75 which swings it clear of strip 19 which may be carried in a recessed channel in table 11. Arm 75 is mounted in and operated by a spring return solenoid 76 which is connected to control panel 43 by lead wires 77. Heating element 78 is mounted on table 11 directly above closure mold 74 and is connected to a suitable source of power.

The operation of the various elements is controlled by event timing wheel 81 shown with ten segments by way of example only. Wheel 81 is rotatably mounted on frame 10 or table 11 by pivot 82 and driven by motor 83 with a small friction wheel 84 which bears against the outer edge of wheel 81. A cable bar 85 is mounted on pivot 82 and control panel 43 and carries a series of micro-switches connected to the various terminals of control panel 43. Control panel 43 may be provided with a power supply bus bar to which one side of each of the pairs of terminals thereon is connected and a bus lead to which one side of each of the micro-switches on cable bar 85 is connected. Cable 86 is carried by bar 85 and connects the load side of each micro-switch to the load side of the corresponding pair of lead wires connected to control panel 43. Leads 87 supply power to the bus bar and bus lead.

That form of the invention which utilizes closure elements 36 and forms a package 88 of eight units 52 is provided with an event timing wheel 81 with events as shown in FIGURE 2. Five micro-switches 89, 90, 91, 92 and 93 of the mercury tilt type are spaced along cable bar 85 to correspond with five event circles 94, 95, 96, 87 and 98 on wheel 81.

The outer circle 94 is provided with eight cam-like projections 99 positioned at the leading edge of each segment 100-107, inclusive, which tilt mercury switch 89 and connect circuit 58 and solenoid 56 across the power supply to actuate arm 53 position unit 52 on strip 19 over aperture 12.

Circle 95 is provided with eight cam-like projections 110 centrally located in each of the segments 100 to 107, inclusive, to cause switch 90 to connect circuit 44 and solenoid 42 across the power supply.

Circle 96 is provided with eight cam-like projections 111 located adjacent the trailing edge of segments 100 to 106, inclusive, and 108 to cause switch 91 to connect circuit 60 across the power supply and energize motor 59.

Circle 97 is provided with a single cam-like projection 112 positioned in segment 107 to close switch 92 just before switch 90 opens. Switch 92 places circuit 48 across the power supply and actuates plunger 46 when tube 29 is in its lowest position. Switch 92 opens when tube 29 has returned the distance of the thickness of one closure unit 36. In view of the critical character of this last action it may be desirable to actuate and release plunger 46 by having tube 29 or piston 32 operate a switch in

circuit 48. A mercury tilt switch in circuit 48 could be closed by a trip when tube 29 is in its lowest position and opened by a second trip when tube 29 has been raised the thickness of one closure unit 36.

That form of the invention which utilizes top closure forms mold 74 and forms a package 113 is provided with an event time wheel 114 which is similar to wheel 81 in the first seven segments 100 through 106, inclusive, as shown by segments 115 through 121, inclusive. Segment 122 closes circuits 58 and 44, respectively, in the same time sequence as in segment 107 of wheel 81, but circuit 48 has been eliminated. In segment 122, circle 97, cam-like projection 125 closes switch 92 and connects circuit 77 to the power supply, actuating solenoid 76 and placing top mold 74 over aperture 12. Switch 92 also closes circuit 72 and places solenoid 66 across the power supply through delay device 73, thus assuring top mold 74 ample time to reach its position over aperture before package engaging portion 70 forces the package 113 upward, so that form 74 folds the upper flaps of package 113 over and seals them.

Package 88 usually contains six, eight or ten merchandise units 52 each contained in individual nested cup-shaped members 126 having their bottoms spaced apart to form compartments.

The walls of the members 126 are relatively long, establish a substantial overlap with a nested member and closely approach the bottom of the second next adjacent nested cup, leaving a narrow annular band 127 of single thickness of material such that the strength of the package 88 as a column is but slightly decreased and the opening of a single individual compartment is greatly facilitated. It is only necessary to force a fingernail against narrow band 127 to give rise to a relatively high localized stress in shear in this narrow strip of single thickness. The closely adjacent edge of the double wall portion provides a stiff resistant shearing edge which cooperates with the fingernail much like the blades of a pair of scissors. Where the cup members 126 are made of heat sealing cellulose or other coated sheet material the nested members 126 are sealed together by a ring of sealing material adhering to the outside of the cup-shaped member 126 adjacent its bottom and adhering to the inside of the next adjacent member 126 below adjacent to its top, forming a strong unitary structural member of the nested cup members 126. Closure 36 is preferably a little larger than the units 52 to assure a good seal under pressure as the cups 126 pass heat ring 128 surrounding tube 15. For quicker setting of the heat seal, particularly for package 113, the heating effect of ring 128 is localized by making it part of the inner wall of tube 15 and insulating ring 128 from the rest of tube 15 with fiber, porcelain, wood or the like. Where desired, as with medicaments, closure 36 may be a folded coiled direction sheet.

Package 113 differs from package in the top closure which is formed by folding over wall portions 129 of the uppermost cup member 126 and heat sealing them. Portions 129 should butt seal together in the center and overlap radially without the necessity of adding an outer paper disc seal. However, such thin seals can be substituted for resilient column 35 and added at the final punch operation for each package 113 if desired. To allow for variations and assure a complete closure a drop of liquid cellulose acetate cement may be added by top mold 74 to the center 130 during the forming step. Again, wall portions 129 may be of such length that they extend slightly beyond center 130.

The operation of the machine and formation of the package 88 is as follows:

Tube 51 is filled with units 52 to be packaged and an adequate supply from a hopper or other source is at hand. Strip 19 is advanced to stop 23 and covers aperture 12. Event timing wheel 81 is driven slowly counter-clockwise

by its motor. As segment 100 passes under cable bar 85 projection 99 tilts mercury switch 89 in FIGURE 2. Switch 89 closes circuit 58 and energizes spring return solenoid 56 which swings arm 53 with unit 52 in curved face 54 into position over aperture 12 above which unit 52 is supported by heat sealing cellulose acetate strip 19. Switch 89 opens as projection 99 passes, breaking circuit 58 and releasing solenoid 56. Arm 53 returns under spring action and another unit 52 to be packaged is dropped into place from tube 51. Tail portion 55 supports the column of units 52 in tube 51 until arm 53 is returned.

Projection 110 in segment 100 closes switch 90 and circuit 44, operating valve 41 and admitting air under pressure from reservoir 39 through pipe 40 to the chamber formed by the closed upper portion of guide sleeve 24 and piston 32. Piston 32 moves downward under air pressure carrying tube 29, and cutter member 25 with it. Cutting edge 26 dies out a blank from strip 19 and radial knives 27 produce radial slits or wedge-shaped cutouts where a small die 28 is used. While FIGURE 3 shows cutting edges it will serve also to illustrate the died out blank. At the same time knife edge carried on member 25 squares off the end of strip 19. This action stops the descent of member 25, but tube 29 continues to descend, compressing spring 34 and increasing the compression of spring 37. As tube 29 descends farther the closure elements 36 held therein press upon the unit 52 positioned on the died out portion of strip 19 and press both into aperture 12. The conical side of element 13 bends the periphery of the cut portion of strip 19 upward, causing the slit parts to overlap. When switch 90 opens after the passage of projection 110, circuit 44 is broken, releasing solenoid 42 and closing valve 41 which discharges the air acting on piston 32 rapidly into the atmosphere. Spring 37 then restores tube 29 and cutter member 25 to their original positions. Projection 111 closes switch 91 and circuit 60, operating motor 59 and advancing the squared end of strip 19 to stop 23.

The above sequence is repeated for segments 101 through 106. In segment 107 projection 111 is omitted and on circle 97 a short projection 112 is positioned to close switch 92 just before switch 90 opens. That is, circuit 48 is closed and pointed armature 46 is forced through slot 50 and impinges upon the column of closure members 36 within tube 29 when the bottom closure member 36 has pushed the eighth unit 52 of the package 88 into tube 15. On the release of air through valve 41 tube 29 rises under the action of spring 37, but the column of closure members 36 is held stationary by armature 46 just long enough to deposit the bottom closure member 36. Switch 92 then opens and spring 49 withdraws armature 46 through slot 50, permitting the column of members 36 to rise with tube 29.

Closure members 36 are coated with the same heat sealing material as strip 19. As the died out portions of strip 19 are formed into cup-shaped members 126 they are sealed together by heat sealing ring 128 which is connected to a suitable source of power and is preferably insulated from tube 15 which cools and sets the heat sealing material.

Projection 111 in segment 108 causes the advance of strip 19 to stop 23 and the next package is formed and forces the preceding package through tube 15 which may be connected to a tube of slightly larger diameter so that the packages may be carried to a boxing platform by vacuum. The slot 71 will admit sufficient air to prevent any such vacuum from affecting strip 19 over aperture 12. As previously noted, all trim from the punch operation is removed by vacuum. Closure members 36 may carry any identifying indicia or printed material on their tops or bottoms.

The formation of package 113 is achieved by an event wheel 114. The first seven segments 115-121 are the

same as on wheel 81. In segment 122 projections 99 and 110 operate as in segment 107, but circle 97 contains a projection 125 timed to operate after projection 110 has permitted switch 90 to open. Projection 125 closes switch 92 and circuits 72 and 77. Solenoid 76 swings heated top forming mold 74 over aperture 12 and solenoid 66 causes lever face 70 to force the package 113 upward so that the wing portions 129 of the top cup 126 are folded over the top unit 52 and heat sealed in place. Delay device 73 assures that mold 74 is in place when the package 113 is pushed upward by lever 68.

Projection 110 in segment 123 operates tube 29 and the central resilient member 35 pushes the package 113 down again. Where seals are used, a column of seals replaces member 35. The lowest seal adheres to the folded portions 129 which are tacky when warm.

Projection 111 in segment 124 advances strip 19 and the apparatus is ready to form the next package. Portions 129 cool quickly and are no longer tacky as the next package forces the first down tube 15 which is widened enough adjacent end 16 to permit the preceding package to drop of its own weight when the succeeding package is three quarters formed. When the vacuum conveying tube mentioned above is used, the first package is removed as soon as it is pushed low enough to close slot 71 and is subjected to atmospheric pressure. The first package 113 of course must be removed to permit lever 68 to pass through slot 71 and function.

Squaring knife may be eliminated by packaging rectangular units 52 or placing a cutting edge such as 130 on wheel 22 the circumference of which is the same as the length of a died out portion. By positioning the rolls 21 and 22 within one circumference of aperture 12, the need of a special holding means is eliminated.

It is contemplated that normal safety circuits may be incorporated in the device so as to stop event wheel 81 or 114, should packaging wrapper material 17, closure elements 36 or units 52 to be packaged become exhausted. Such safety controls are well known in the art and may take the form of switches in series in the circuit of motor 83. These switches function to open the motor circuit in the event of the exhaustion of any one of the three supplies mentioned above.

The form of the invention shown in FIGURES 7 through 23 utilizes a table 11 on which two main supports carry an apparatus in which there is an aperture of such size as to receive articles to be individually packaged. The aperture is surrounded by a depending tube with a flaring lip. A roll of suitable wrapping paper or the like of desired width, is disposed at one side of the table and carried on feed bands equipped with steel points and operated by means of a mechanical device advancing the paper equal distances at each cycle. A die punch located directly above the aperture operates while the paper is stationary and cuts a suitable blank for forming a wrapping element. The edges of the blank may be tongued or not, as desired. A punch which is associated with the die structure forces the paper into the flaring mouth of the aperture of the tube. The article or unit to be wrapped is then deposited in the dish-like or cup-like compartment through the plunger or by mechanical side construction. There is sufficient margin provided on the paper blank to leave an upstanding annular collar extending well above the article to be wrapped. The article rests within the dish-like or cup-like compartment, the top of which is open. The feed bands advance the paper strip so that it again covers the aperture and article. The die again descends, cuts a second blank, and the punch forces the second blank into the aperture and into the cup-like compartment formed by the first wrapper element with which it nests to form a closed compartment containing the first article. The second blank will be seen to form a cover for the first article and the marginal portion of the first blank will extend up around the sides of the second blank.

This operation is repeated and the articles force each

other down the tube or magazine which, after the bell mouth portion is passed, forms a smooth, perfectly circular channel which presses the overlapping portions of the nesting wrapper elements into adhering relation. If desired, circumferential contact plungers that are controlled with adjustable springs to control friction, may be supplied. A solenoid control releases the plungers and the finished package may be allowed to drop out of the tubular magazine into a package case or pass on to the station for the next operation.

As noted above in connection with the structure of FIGURE 1, the proportions of the tubular members 15 and 216 may be such that they supply ample friction for the packaging step and successive packages force finished packages through the tubular member, the diameter of which may in itself provide sufficient resistance to assure proper nesting of the package segments, into the shipping case or to the next station for successive operation. The tongue portions of the wrapper elements permit easy overlap at the cup forming stage. Where the paper is wax coated or coated with heat sealing plastic material or the like, a portion of the periphery of the tubular magazine may be heated by suitable means such as a heating coil, which causes the marginal overlapping portions of the nested wrapper elements to adhere into a vapor-proof, gas-tight seal which produces a structurally strong, unitary columnar compartmented package. As noted above, the article is entirely enclosed between adjacent nested blanks in an individual sealed compartment. If desired, the die punch structure may be made hollow and the article deposited in a dish-like cup in the aperture from a magazine formed in the hollow portion of the plunger immediately at the start of the return stroke or substantially simultaneously with the dieing out of the dish-like wrapper element in the aperture. A perhaps simpler construction may be obtained by employing a separate mechanical feed for depositing the article in the dish-like cup following the return stroke of the die. This is particularly true where some variation in size must be dealt with. Such structure could be similar to that shown in FIGURE 1.

The form of individual packaging machine of FIGURES 7-23 is operated with a variable speed mechanical drive, preferably an electric motor 200 connected directly to the drive shaft 201 by means of a suitable coupling 202. Mounted on shaft 201 are two revolving cams 203 and 204 which are properly shaped, timed and adjusted for operating an air valve control 209 by raising and lowering the pistons 205 and 206, thereby controlling air flow to and from the main operating cylinder 207 through pipe 208. As cam 202 lifts the piston 205 air which has passed through sensitive reducing control valve 209 enters the valve body at 210 and passes through the valve and pipe 208 to the main operating cylinder 207 as shown in FIGURES 11 and 12. Air entering the main operating cylinder 207 through pipe 208 forces the main piston 211 downward. This piston is equipped with a combined cutting and forming die shown in FIGURE 15.

The cutting die 212 travels slightly ahead of the forming die 213 and after the paper from roll 114 has been cut to size the forming die 213 is allowed to continue its downward stroke under the action of a retarding spring 215 and force the paper from roll 214 comprising coated metal foil or plastic wrapper material, into the dies 212 and 213 and depending tube 216. This action forms a dish-like or cup-shaped wrapper element 250 for enclosing the article being individually packaged. After the downward stroke of the piston 211 has been completed a cam 204 opens the exhaust valve piston 205 and permits the air to exhaust from the cylinder 207, through the valve 209 to the atmosphere.

The piston 211 operates against a pull back air cylinder 217 which is under constant controlled pressure by means of a suitable reducing valve. The piston 211 returns to a normal position as the pressure in the cylinder 207 is released.

Piston 211 is now ready for another stroke as soon as piston 205 operates and opens the valve 209 for air feed to pipe 208 and cylinder 207. A right angle shaft 218 at the end of main shaft 201 is driven by bevel gears 219 and operates band wheels 220 at intermittent timed strokes through a bevel gear 221 and a geneva stop 222. The bands 223 mounted on the wheels 220 advance a predetermined distance and pull the wrapper strip 214 by means of pull pins 224 in the bands that contact and pierce the strip 214 as it is unwound from the supply roll 225 which is mounted on suitable bearings and guides 226 at the end of the machine base. The holes produced by the pull pins 224 must not interfere with or jeopardize the integrity of the individual sealed compartments. 15 Where there is likelihood that the perforations made by the pull pins 224 are not completely and permanently sealed then suitable tension, friction or vacuum means may be provided to assure controlled wrapper supply. Suitable pinch rolls may be used such as the guide roller 226 in FIGURE 20 which may bear against the band wheel.

The pull pins 224 are preferably located at the edges of the band 223 and the perforated part of the wrapper strip 214 is cut off by the die or positioned in the overlapping portion of adjacent nested wrapper elements in the completed package.

A fresh roll 225 of wrapper material can be mounted and started while the machine is in operation as may be seen from FIGURES 7 and 8.

30 Mounted underneath the machine base 228 is a V-belt driven rewind 229 as shown in FIGURES 21-22 for collecting the waste margin of the wrapping strip 214. A slip roll 230 to which the waste is attached rides on two driven rollers 231 and the friction contact with these rollers 231 takes up slack in the paper and forms a roll. The rewind 229 is driven by means of a V-belt connected to the stop cam geneva wheel 222 shown in FIGURE 8.

35 Gearing 240 mounted on shaft 218 drives the mechanism 241 for feeding the articles 242 to be packaged. An article 242 is collected from a feed hopper 243 onto a continuous running belt 244 and forces the article 242 by means of friction into the top of tube or conduit 245. As fast as articles 242 are removed from tube 245 the belt friction forces another article 242 to position. At the bottom of tube 245 are located two slides 246 and 247 that are operated by means of a link 248 connected to the crank wheel 249.

40 An article 242 to be packaged rests on the slide 246 in front of slide 247 and as crank wheel 249 revolves, it forces both slides 246 and 247 forward. A restraining action of spring 261 between the two slides 246 and 247 allows slide 247 to continue the full stroke and push the article 242 off the end of slide 246 into the previously formed paper cup-like wrapper element 250 for nesting and packaging. The slides 246 and 247 then return to normal position and are ready for another cycle.

45 Continuous cycles of the main piston 211 which carries the cutting die 212 and forming die 213 gradually build up a finished package by successive nesting of formed wrapper elements 250 with articles 242 therebetween, as the individual packaged articles and their cup-like nested wrapper elements 250 are forced into the tubular member 216.

50 55 60 65 70 75 Tubular member 216 may be provided with a heat sealing ring similar to 128 for sealing the overlapping side walls of adjacent nested wrapper elements 250 where the coating on the wrapper strip 214 is thermoplastic or heat sealing. Where pressure sealing of adhering coatings is employed heat sealing need not be used.

The member 216 is provided with four heat sealing blades 251 actuated by combined solenoid 252 and spring 253 action which operates intermittently depending upon the number of articles or unitary compartments comprising a package. This number may vary from two com-

partments in a single package to an unlimited number where continuous packaging is done for some types of dispensing machines. In general, however, a package will usually have four, six, nine or twelve articles or units individually packed, though these numbers are not to be taken as limiting.

In the usual package the action of the heat sealing blades 251 is timed to close the last compartment 250 which does not receive a nested cup-shaped wrapper element. Although a closure element 35 or 36 may be used it is not necessary where the four heat sealing blades 251 are provided which slide over the top of the full package, folding and sealing the top portions of top wrapper element 250 as shown in FIGURES 13 and 14.

When a package is being formed and forced into the tubular channel member 216, two plungers 254 actuated by springs 255 and released by solenoids 256, produce resistance against the side of the package until it is full and sealed. It will be understood that for many applications the tubes 15 and 216 may be proportioned to provide sufficient resistance against the side of the package and that resistance plungers 254 may be eliminated, the relative size of the tube with respect to the package segments furnishing the necessary resistance required to assure proper nesting and package formation. The four sealing blades 251 and two resistance plungers are operated by individual solenoid action which is controlled by properly timed, cam operated micro-switches 257 connected to shaft 218 for timed sequence operation. A timing event wheel such as shown in FIGURE 2 may also be used when properly synchronized. The cams for operating the micro-switches are mounted on a counter shaft 258 driven by shaft 218 through pinion 259 and gears 260.

Following the sealing of the top of the finished package by blades 251, the resistance plungers 254 are released by the solenoid control which energizes solenoids 256 and the finished package is dropped from tubular magazine 216 into a shipping box, irradiation chamber 401, vending device or apparatus for performing the next function, i.e., flash freezer, vacuum chamber compartments 401 or separate chambers 401, followed by a chamber with a selected gas under pressure, high frequency cooking, pasteurizing chamber or the like. Where vacuum and gas filling are employed, the sealing ring 118 which may also carry high frequency current may be placed on tubular channel member which may incorporate vacuum and gas pressure channels 400 and 402 as a part thereof in advance of the sealing ring position.

Package sealing and releasing for different sized packages of four through twenty-five or more compartments may be controlled by changing one gear 261 on the cam shaft 258 to produce the particular package required.

Where pre-formed cups such as those shown in FIGURE 10a are used, positioning structure similar to elements 51 through 58 of FIGURE 1 may be used and then strip feed and cutting die 212 may be eliminated.

It is within the scope of the invention to combine the above apparatus in its several forms including those described below with a controlled irradiation chamber or chambers 401 whereby the packaged products may be irradiated when in the package so as to assure against possible contamination. Where control is sufficiently close to guard against possible contamination, the irradiation step may take place as shown in FIG. 23 during or just prior to the actual packaging step. It will be understood that the packaging device and the packages themselves may be incorporated as part of a coin controlled vending machine whereby the packages may be dispensed from automatic machines in any desired quantity at any desired price. As is usual in such cases, machines of this type make change and display the several commodities being vended. The machine may be dial type, wherein the purchaser may select the number

of packaged units which he wishes to purchase and in which the selected number may be cut from a long columnar package. For this purpose the packaging machine itself may be continuous and need not necessarily produce packages with a pre-selected number of compartments, though such a package with a pre-selected number of compartments is probably preferable for many types of marketing, including automatic vending machines. Where highly elastic plastic sheets or envelopes are used for the packaging means, it will be understood that the compartments may be achieved by merely twisting the cylindrical wall of the columnar package between measured units of the packaged product. For this purpose alternate segmented unit portions may be rotated in opposite directions to achieve the complete twisted enclosure of adjacent compartments. Plastic material of this type may be pliable for only a limited period, after which it may set into the packaged form. Again, the twisted portion may be composed of material which adheres to adjacent twisted surfaces so as to assure an adequate seal between compartments. Where plastic material of this type loses its plasticity and sets after a period of time, which may vary from a few hours to a matter of days or even months, this type of package may be more readily opened compartment by compartment without a knife or similar implement.

In regard to the irradiation of the packaged material, reference is made to the report of the Committee on Foods of the symposium on irradiation sterilization of foods of the National Academy of Science National Research Council Advisory Board on Quartermaster Research and Development, held at Cambridge, Massachusetts, June 26, 1953.

The packages shown in FIGURES 1a through 12a show a number of similar units 20' of substantially cup-shape within an outer wrapper 21' which grips the units 20' and forms the package. Wrapper 21' may be a cylinder made up from a rectangular sheet or it may be a helix made up from a long narrow strip with or without the inwardly projecting edge disclosed in the first patent mentioned above. Between each of the units 20' is a partition member 22' which is preferably circular but may be of any desired outline. Member 22' preferably has a certain stiffness but may be of the same material as wrapper 21' if desired. Wrapper 21' and partition member 22' may be of waxed paper, metal foil, regenerated cellulose, or any of the materials mentioned previously. They may be treated with waterproofing and sealing compounds common to the art, comprising wax, plastic coatings, and the like. Such compounds may be heat sealing if desired. Partition 22' may be thickened at its edge as at 23' so as to form a better joint 24' with wrapper 21'. Enlarged partition 23' may be formed by the material of partition 22' or it may be a concentration of sealing compound or both. Partition 22' may be of substantially the same diameter as units 20' and so contact wrapper 21' without indentations as 25'.

In FIGURE 5a partition 22' is adhered to the sides of indentations 26'. Where a helical wrapper is used, the edge may be folded over slightly after the manner taught in the above first mentioned patent. Partition 22' may merely rest or may be adhered to the in-turned flange counterpart of 26'. With only a slight turn-in a helical wrapper 21' does not cover the entire inner face of the unit 20'.

FIGURE 6a presents a modified partition 27' shaped like a saucer with a projecting rim 28' the outer portion of which may be adhered to wrapper 21'. Here again wrapper 21' may be formed from a narrow strip wound in a helix, if desired, or a group may be assembled with the partitions 27' in place and all wrapped together in a rectangular sheet.

FIGURE 9a shows a development of the concept of FIGURE 6a. Here partitions 30' have become relatively deep and cup-shaped with high walls 31' which receive

the bottom of the one next above. High walls 31' may be adhered to the bottom side portions next above and form a complete package without the aid of wrapper strip 21'. Wrapper 21' may, however, be used with the structure of FIGURE 9a as in FIGURE 6a. Adherence may be obtained through the agency of a heat sealing coating on the material of cups 30' such as is common in the "cellophane" packaging art. Again, contact sealing may be obtained by using a latex sealing compound on the outside near the bottom of cups 30' and at the inside near the top. Of course any suitable adhesive may be used. The package may be closed by reversing a cup 30' at the upper end or folding over and sealing the upstanding walls 31'. A disc closure such as 32' may be used to which the upstanding walls 31' of the top cup can be adhered.

Normally walls 31' have enough flare and give to receive the bottom of the unit next above in snug, close-fitting relation. However, a reduced portion 33' may be employed or the walls 31' may be regarded as enlarged. This allows for the lap and produces a smooth package. This last is thought to possess its main value when the units 20' are large or heavy and it becomes necessary to increase the thickness of the elements 30' accordingly. Slits 34' may be used to facilitate interfitting and forming of the cup-shaped elements 30'.

FIGURE 12a presents a modified form of the invention in which wrapper 35' is preferably formed of a tube of heat sensitive material such as "Pliofilm" or the like. Heated arms or finger members bring the tube material together between units 20' and seal off each in an individual compartment. This action may be partly accomplished by fullness of material of the tube 35' between units 20' or by the yielding of the material under the action of heat or force or a combination of the two. If desired, an actual or partial severance of the walls 35' may be made at the joints 36' whereby easy separation of the units may be accomplished. Under such circumstances a partial fusion of the wrapper or its coating may be utilized to hold the package together or an outer cylindrical wrap may be employed. Where Pliofilm or the like is utilized as recommended, and the several units are twisted, the package may be produced by an apertured tube in which rollers contact the peripheries of the stacked units 20' within a Pliofilm cylinder and twist the individual segments of the cylinder with its individual unit 20' a desired amount, so that each compartment is sealed off. For this purpose, three wheels are preferably used together for each unit. Groups of wheels being applied to adjacent units may be made to rotate at different speeds or in opposite directions to produce the desired twist for individual compartments. Again, the twist may be of such character as to pre-stress the Pliofilm or other wrapping material both to produce firm adherence or fusion and to aid in opening the individual compartments of the package without disturbing other compartments.

It will be noted that each article is packaged with its own individual compartment, the opening of which in no way disturbs the remaining articles. Where the wrapping material is used, contrasting colors can be used effectively to bring out the individualized compartments of the package.

In FIGURES 1b-6b the package is made up of a number of similar units 20" such as mints, tablets, discs, nuts or any of the items mentioned. While the units 20" need not be round, they should preferably be sufficiently uniform in shape to be handled by automatic machinery. An outer wrapper 21" grips the units 20" and forms the package. Wrapper 21" may be a cylinder made up from a rectangular sheet or it may be a helix built up from a long narrow strip with or without the inwardly projecting edge disclosed in the patent mentioned above. Between each unit is a partition member 22" which is usually circular, but may be of any desired outline. Mem-

ber 22" preferably has a certain stiffness, but may be of the same material as wrapper 21" if desired. Wrapper 21" and partition member 22" may be of waxed paper, coated metal foil, plastic material, regenerated cellulose, "Saran," "cellophane," "Pliofilm," polyethylene, vinyl plastic, or the like. They may be treated with waterproofing and sealing compounds common in the art. Such compounds may be heat sealing if desired. Partition 22" may be thickened at its edge as at 23" so as to form a better joint 24" with wrapper 21". Enlarged portion 23" may be formed by the material of partition 22" or it may be a concentration of sealing compound or both. Partition 22" may be of substantially the same diameter as units 20" and so contact wrapper 21" without indentations such as 25".

In FIGURE 5b partition 22" is adhered to the sides of indentations 26". Where a helical outer wrapper is used the edge may be folded over slightly after the manner taught in the above mentioned patent. Partition 22" may merely rest on or may be adhered to the in-turned flange counterpart of 26". With only a slight turning in a helical wrapper 21" does not cover the entire inner face of the unit 20.

FIGURE 6b presents a modified partition 27" shaped much like a saucer with a projecting rim 28" the outer portion of which may be adhered to wrapper 21". Here again wrapper 21" may be formed from a narrow strip wound in a helix if desired, or a group may be assembled with the partitions 27" in place and all wrapped together in a rectangular sheet, making a cylindrical package.

FIGURE 9b shows a development of the concept of FIGURE 6b. Here partitions 30" have become relatively deep and cup-shaped with high walls 31" which receive the bottom of the one next above. High walls 31" may be adhered to the bottom side portions next above and form a complete package without the aid of wrapper strip 21". Wrapper 21" may, however, be used with the structure of FIGURE 9b as in FIGURE 6b. Adherence may be obtained through the agency of a heat sealing coating on the material of cups 30" such as is common in the "cellophane" packaging art. Again, contact sealing may be obtained by using a latex sealing compound on the outside near the bottom of cups 30" and at the inside near the top. Of course, any suitable adhesive may be used. The package may be closed by reversing a cup 30" at the upper end or folding over and sealing the upstanding walls 31". Of course, a disc closure as 32" may be used to which the walls could be adhered.

Normally, walls 31" have enough flare and give to receive the bottom of the unit next above in snug, close-fitting relation. However, a reduced portion 33" may be employed or the walls 31" may be regarded as enlarged. This allows for the lap and produces a smooth package. This last is thought to possess its main value when the units 20" are large or heavy and it becomes necessary to increase the thickness of the partition elements 30" accordingly. Slits 34" may be used to facilitate interfitting and forming of the cup-shaped elements 30".

FIGURE 12b presents a modified form of the invention in which wrapper 35" is preferably formed of a tube of heat sensitive material such as "Pliofilm" or the like. Heated arms or finger members bring the tube material together between units 20" and seal off each in an individual compartment. This action may be partly accomplished by fullness of material of tube 35" between units 20" or by the yielding of the material under the action of heat or a combination of the two. If desired, an actual severance of the walls 35" may be made at the joints 36" whereby easy separation of the units may be accomplished. Under such circumstances a partial fusion of the wrapper or its coating may be utilized to hold the package together or an outer cylindrical wrap may be employed.

The packages disclosed in FIGURES 9b-16b are prod-

ucts of the machine disclosed in copending application Serial No. 92,476, and are in general formed by nesting the individual elements 126" by pressing a sheet of material into a tube with the material to be packaged centered thereon, forming a cup surrounding the material, nesting a second cup therewith and heat sealing the two together.

In FIGURES 13b and 14b the individual cup-shaped members 126" may be formed of regenerated cellulose such as "cellophane" with heat sealing waterproofing coatings, thermoplastic materials such as "Pliofilm," methyl-methacrylate films, as well as many others. Preferably such films are transparent to disclose the contents of the individual compartments or units and may be of contrasting colors which may be employed effectively to bring out and emphasize the individualized compartments of the package. Again, where two or more adjacent compartments are to be used simultaneously, as for example tea and sugar, they may be of the same distinctive color. In any given package colors may be used alone or with indicia to indicate sequence of use or combination or other treatment of the separate contents of the individual unit compartments. In pharmaceuticals, dangerous or sensitive materials in a package may be distinctively indicated.

Metal foils may be used alone or in combination with the above materials to shield a complete package or a portion thereof from possible deleterious effects of light or other radiation. Metallic coatings may, of course, be sprayed or painted on the members 126" or some of them, and wave-length selective filter materials may be used both to protect the contents and permit inspection without destruction of the package.

The cup shaped elements 126" may be preformed as shown in FIGURE 11b or may be formed at the time the material is packaged as shown in FIGURES 9b and 13b-16b. The package 88" usually contains six, eight or ten merchandise units 52" each contained in and separately packaged in the individual nested cup shaped members 126" discussed above and having their bottoms spaced apart to form compartments. The walls of the members 126" are relatively long, establish a substantial overlap with a nested member and closely approach the bottom of the second next adjacent nested cup, leaving a narrow annular band 127" of single thickness of material such that the strength of the package 88" as a column is but slightly decreased and the opening of a single individual compartment is greatly facilitated. It is only necessary to force a fingernail against narrow band 127" to give rise to a relatively high localized stress in shear in this narrow strip of single thickness. The closely adjacent edge of the double wall portion provides a stiff resistant shearing edge which cooperates with the fingernail much like the blades of a pair of scissors. Where the cup members 126" are made of heat sealing cellulose or other coated sheet material the nested members 126" are sealed together by a ring of sealing material adhering to the outside of one cup shaped member 126" adjacent its bottom and adhering to the inside of the next adjacent member 126" below adjacent to its top, forming a strong unitary structural member of the nested cup members 126". Closure 36" is preferably a little larger than the units 52" to assure a good seal under pressure as the cups 126" pass heat ring 128" surrounding tube 15". For quicker setting of the heat seal, particularly for package 113", the heat effect of ring 128" is localized by making it part of the inner wall of tube 15" and insulating ring 128" from the rest of tube 115" with fiber, porcelain, wood or the like.

In FIGURE 13b a top closure such as 136" is used, preferably a little larger in diameter than the units 52" to assure a good seal under pressure as the walls of cups 126" pass by the heat sealing area in the forming tube described in application Serial No. 92,476. Allowance is thus made for the fewer layers of material on the sides of closure 136". Where desired, as with medicaments,

products for home use and the like, the closure 136" may be a folded or coiled direction sheet.

In FIGURE 14b the package 113" differs from package 88" which is formed by folding over wall portions 129" of the uppermost cup member 126" and heat sealing them. Portions 129" should butt seal together in the center and overlap radially without the necessity of adding an outer paper disc seal. However, such thin seals can be substituted for closure 36" and added at the final punch operation for each package 113" if desired. To allow for variations and assure a complete closure a drop of liquid cellulose acetate may be added to the center 130" during the forming step. Again, wall portions 129" may be of such length that they extend slightly beyond center 130".

The overlapping of wall portions 129" as shown in FIGURES 15b and 16b of packages 200" and 300" comprise a preferred form of the invention at present because care need not be exercised to obtain exact registration as with FIGURE 14b where the wall portions must meet without buckling. In package 201" the contents 201" may be coffee, tobacco, tea, sugar, headache powder, putty, butter pats, cheese portions, olive oil, flour, corn meal, dehydrated potato, muffin mix, prepared rolls, ice cream, sundaes, custard, cream, fruit, processed eggs, individual first aid dressings or the like. In package 300" the contents 301" may be one or two bread slices, buttered bread, sandwiches, cake, waffles, beef hamburger patties, minute steaks, pork chops, crab cakes, individual meat pies, vegetables, tarts, first aid dressings for large areas, moist plasters and the like. An outer wrapper 302" is provided to give added security against contamination and added strength against rupture. The wrapper 302" will serve the major part of its function if it is applied only to that portion of the package 300" which is contained between the arrows A—A in FIGURE 16b. The overlapping seal 131" of the wall portions 129" is sufficiently strong to provide a secure closure without the addition of an outer wrapper 302". An unsealed free end portion 132" of the overlapping wall 129" may be left for ease in opening if desired. In the same way a free unsealed lip portion may be left at 133" for ease in opening if desired. Opening elements 127" and 132"

40 may be used alone or together as desired. 45 Where the material 201" or 301" is soft and yielding, deforming readily under pressure, there is some danger that the packages 200" and 300" may not retain their desired shape. In such cases stiffening inserts 203" of suitable configuration are placed within the cups 126" just prior to or at the time of inserting the material 201" or 301". A bottom member 204" may be placed on the bottom of each cup 126" or may carry the material being packaged at the time of introduction and is packaged with it. Member 204" shown in FIGURE 19b may be formed somewhat in the manner of element 27" of FIGURE 8b to give some support at the edges. While members 203" and 204" may be of help in effecting a satisfactory seal between individual compartments, the packaging machine itself can usually be relied upon to produce such action.

60 FIGURE 17b shows a modification of the invention in which the individual compartments are formed from a tube or from two sheets of packaging material, folded compactly in side-by-side relation and enclosed in an outer supporting wrapper. A tube 400" of suitable thermoplastic material is sealed at spaced intervals 401" providing individual compartments 402" therebetween containing material such as 201" and 301" or the like. A cylindrical outer wrapper 403" fits snugly around the side walls and seals 401" of compartments 402" and is sealed thereto at the areas of contact 404". The central line of these areas may be partially perforated at 405" to promote ease of opening without unduly weakening the structure or integrity of the package. Where it is desired to eliminate the outer wrapper 403" the internal walls of

compartments may be sealed together at 496". Although the compartments 402", as well as those in FIGURES 9b and 13b-16b, need not all be of equal size, it is usually better to make them equal or at least to provide a fixed sequence of recurrence where size difference is a factor and automatic packaging is desired.

All of the packages above described may be irradiated and if desired, an outer enveloping wrap of heavy lead foil or sheet in addition to wrapper 403" or 21" may be employed in the cases where the demands are most exacting. Tearing strips, "V" cuts at an edge of the plastic material, slits, scores and perforations may be used in selected cases, where danger of premature opening or breaking of the seal is negligible, to promote opening of the individual compartments. In general, however, those described in detail above will suffice.

The antibiotics mentioned above comprise various natural molds, synthetic chemical compounds, and related products which either kill, sterilize or inhibit bacterial growth. They presently comprise the penicillins, the aureomycins and the sulpha compounds, but it is not intended to limit the invention to the use of any particular one of these classes or drugs representative thereof, it being intended to use that one or combination of such antibiotics as will produce the maximum preserving effect for food and other products with a minimum of disagreeable or undesirable side effects such as undesirable changes in taste, color, food value, toxicity or the like. Of the sulpha drugs, sulphanilimide, sulphadiazine, sulphathiazole may be taken as representative. Other chemical products having the same general effect such as, for example, tetracycline, may also be employed.

While there have been presented above particular embodiments of the invention now believed to be preferred, many variations will readily suggest themselves to those skilled in the art in the light of the above disclosure. All of these different forms which fall within the spirit of the invention are intended to be covered by the appended claims wherein generic terms are employed for the express purpose of including the many equivalent structures by which the present results may be obtained.

I claim:

1. In combination in apparatus for packaging a plurality of articles separately in individual compartments, means to position said articles for wrapping, means to nest successive individual wrapper elements with at least one article therebetween and with overlapping side walls, said means to nest comprising plunger means, means to move said plunger means into nesting position, means to withdraw said plunger means from nesting position, and resistance means opposing the force of said plunger means to assure proper nesting action, means to cause contiguous walls of successive wrapper elements to adhere to provide a unitary package having sealed compartments for said articles to preserve the contents of said compartments individually and separately whereby each compartment and its contents is maintained in a desired state of preservation independently of the rupture or contamination of an adjacent compartment of the package formed by the combination.

2. The combination set forth in claim 1, in which said individual wrapper elements comprise pre-formed cups capable of nesting one with the other to provide overlapping side walls.

3. The combination set forth in claim 1, and means to preserve the contents of said sealed compartments.

4. The combination set forth in claim 1, in which said resistance means comprises constricting means positioned to act on the side walls of the overlapping wrapper elements.

5. The combination set forth in claim 4, in which said means to nest comprises an elongate tube having a tapered mouth, said resistance means comprising controlled movable plungers mounted on opposite sides of said tube below said tapered mouth.

6. The combination set forth in claim 4, in which said plunger means comprising a combined cutting means and forming die for die cutting individual wrapper elements from an elongated strip, and said means to nest comprising a cylindrical channel means having a flared mouth, said plunger means being formed to fit below the flared mouth of said cylindrical channel means.

7. The combination set forth in claim 6, said channel means having a circular cross-section, packaging cycle 10 control means for said packaging apparatus comprising air supply means, a motor, cam means geared to said motor, a plurality of air valves controlled by said cam means, and air conduit means leading to said plunger means from said air supply and at least one of said air 15 valves, and means for collecting waste margin material of said elongated strip.

8. In combination in apparatus for packaging a plurality of articles in individual compartments of a unitary segmented package, means to position said articles for 20 wrapping, means to nest successive individual wrapper elements with at least one article therebetween and with overlapping side walls, means to cause contiguous walls of successive nested wrapper elements to adhere to provide a unitary package having sealed compartments for 25 said articles and a plural element closure means mounted for movement transverse to the direction of movement of said wrapper elements and constructed to contact the upstanding side wall of the last of said nested individual wrapper elements.

9. The combination set forth in claim 8 in which said 30 individual wrapper elements comprise pre-formed cups capable of nesting one with the other to provide overlapping side walls.

10. The combination set forth in claim 8, and means 35 for preserving the contents of said package.

11. The combination set forth in claim 8, said plural element closure means comprising opposed pairs of finger means slidably mounted for movement toward each other.

12. The combination set forth in claim 11, said means 40 to nest comprising a tubular member and means mounted to provide resistance to the movement of nested wrapping elements through said tubular member to promote proper nesting of the several wrapper elements comprising a package.

13. The method of packaging a plurality of articles 45 by automatic machinery comprising the steps of placing an article on a cup-shaped first wrapper element, placing a second article on a second cup-shaped wrapper element, nesting said second cup-shaped wrapper element and said first wrapper element with said first article therebetween, controlling the nesting of said first and said second wrapper elements to limit the force exerted between said first and said second wrapper elements during the nesting thereof, providing overlapping side walls of said first and 55 second cup-shaped wrapper elements, placing a third article on a third wrapper element, nesting said third wrapper element and said second wrapper element with said second article therebetween, controlling the nesting of said third and said second wrapper element to limit the force exerted between said third and said second wrapper elements, providing overlapping side walls of said second and said third wrapper elements, continuing said steps to form a compartmental package with a desired number of compartments and sealing together overlapping contiguous side walls of adjacent nested wrapper elements to produce a strong, unitary, columnar package of sealed individual compartments containing said articles.

14. The method set forth in claim 13, the step of 60 forming said cup-shaped wrapper elements prior to packaging.

15. The method set forth in claim 13, and the step 65 of preserving at least some of the articles contained in said sealed individual compartments.

16. The method set forth in claim 15, in which the pre- 75

serving step comprises the application of an antibiotic to at least some of said articles, said step controlling the nesting of adjacent ones of said wrapper elements providing a narrow band of single thickness of wrapper material extending around each compartment whereby opening is facilitated and a smooth contiguous overlap of said side wall portion of adjacent ones of said wrapper elements is provided to assure the completeness of the seal between said overlapping side wall portions.

17. A method of packaging a plurality of similar articles by high speed automatic packaging machinery under controlled substantially sterile conditions comprising the steps of positioning a first preformed cup-shaped wrapper element, nesting a second preformed cup-shaped wrapper element and said first preformed wrapper element with an article to be packaged therebetween, controlling the nesting of said first and second wrapper elements to provide desired overlap of the side walls of said first and said second preformed wrapper elements, nesting a third preformed cup-shaped wrapper element and said second preformed wrapper element with an article to be packaged therebetween, controlling the nesting of said second and third wrapper elements to provide desired overlap of the side walls of said second and said third preformed wrapper elements, continuing said steps to form a compartmented package with a desired number of compartments and sealing together contiguous overlapping por-

tions of the side walls of said wrapper elements to produce a unitary, columnar package having sealed individual compartments containing said articles.

18. The method set forth in claim 17, said wrapper elements being of heat sealed cellulose acetate whereby the packaged articles are clearly visible through a double layer of wrapping material, and said step of controlling the nesting of adjacent ones of said wrapper elements providing a narrow band of single thickness of material around each compartment whereby opening is facilitated.
